UNITED STATES PATENT OFFICE.

WILLIAM QUISENBERRY, OF FORDSVILLE, KENTUCKY.

CAR-COUPING.

SPECIFICATION forming part of Letters Patent No. 587,452, dated August 3, 1897.

Application filed November 4, 1896. Serial No. 611,021. (No model.)

To all whom it may concern:

Be it known that I, WILLIAM QUISENBERRY, a citizen of the United States, residing at Fordsville, in the county of Ohio and State of Kentucky, have invented certain new and useful Improvements in Car-Couplers; and I do hereby declare the following to be a full, clear, and exact description of the invention, such as will enable others skilled in the art to which it appertains to make and use the same.

This invention relates to improvements in car-couplers; and it consists of certain novel constructions, combinations, and arrangements of parts, all of which will be hereinafter more fully described and claimed.

In the accompanying drawings, forming part of this specification, Figure 1 represents an end elevation of a car provided with my invention. Fig. 2 represents a central vertical section through one of my improved couplings. Fig. 3 represents an enlarged detail perspective view of one of my improved coupling-links, and Fig. 4 represents a similar view of a modified form of link.

A in the drawings represents the car; B, the draw-head; C, the coupling-link, and D the locking piece or pin.

The draw-head B is mounted below the end of the car in the ordinary manner and is of the usual construction, with the exception that it is provided with a socket b and a vertical slot b', opening into the same.

The coupling-link C is formed at each end into a conical point c, and is provided with a middle annular flange c' and horizontal grooves c². When the said link is passed into the draw-head, the annular flange c' abuts against the outer end of said head, so as to bring the groove c² directly below the slot b'. The said link is then locked in the draw-head by the said locking piece or pin D, which projects down through the slot b' into the groove c². The said locking piece or pin is held down in this position by a heavy spring d. The said pin D is mounted upon a pivoted lever d' and is normally held down by said spring d. The opposite ends of the said spring are supported by a yoke or frame d², suitably mounted upon the platform of the car and provided with vertical arms d³ d³, to which the outer ends of said spring are

connected by links d⁴ d⁴. The said lever d' is pivoted upon one of said vertical portions d³, the opposite end of said lever being connected to an operating-rod d⁵, which in turn is connected to a pivoted lever d⁶, operated by a cord or chain d⁷.

It will be observed from the foregoing description that when one of the conical points c enters the socket b of the draw-head it forces the locking-pin D upward against the tension of the spring d until one of the grooves c² coincides with the slot b', when said pin D again descends under the tension of the spring d, and thus locks the link firmly in position in the draw-head.

When it is desired to uncouple the cars, a ring d⁸, connected to the lower end of the cord d⁷, is pulled downward, thus elevating the rod d⁵ and raising the outer end of the lever d', which carries the link-pin D therewith. The springs d are preferably constructed of graduated layers in a manner similar to carriage-springs.

In the modified form of connecting-link shown in Fig. 4 I provide only one of the conical points and lateral grooves, the portion of the link lying to the side of the annular flange or ring being provided with an eye f, that may be secured in the ring link-and-pin coupling. This form of coupling is intended for use when a car provided with my improved coupling-head and a car provided with the ordinary coupling-head are to be connected.

It will be observed from the foregoing description that while the action of the coupling is altogether automatic the parts of the same are so connected as to be positive proof against any accidental uncoupling, and a strong and effective coupling is provided.

Having thus described my invention, what I claim as new, and desire to secure by Letters Patent, is—

1. In a car-coupling, the combination with a socketed draw-head having a vertical slot, of a coupling-pin adapted to be projected through said slot to engage the groove in the link, a pivoted lever carrying said pin, a bow-spring engaging said lever to force the same normally down, a supporting-yoke mounted upon the truck, and pivoted links connecting

the upwardly-extending ends of said yoke and the ends of the spring, substantially as described.

2. In a car-coupling, the combination with 5 a socketed draw-head having a vertical slot, of a coupling-pin adapted to be projected through said slot to engage the groove in the link, a pivoted lever carrying said pin, a bow spring engaging said lever to force said pin 10 normally down, and a supporting-frame mounted upon the truck for supporting the ends of said spring, substantially as described.

3. In a car-coupling, the combination with 15 a socketed draw-head having a vertical slot, of a coupling-pin adapted to be projected

through said slot to engage a groove in the link, a pivoted lever carrying said pin, a spring for normally holding said lever down, a pivoted operating-lever mounted upon the 20 car, a link connecting this lever and the before-mentioned lever, and a pendent cord for actuating said operating-lever, substantially as described.

In testimony whereof I have signed this 25 specification in the presence of two subscribing witnesses.

WILLIAM QUISENBERRY.
